UNITED STATES PATENT OFFICE

117,471

DESIGN FOR A COMBINATION FIRE GRENADE AND SUPPORT

Powell Evans, Haverford, Pa.

Application November 29, 1938, Serial No. 81,463

Term of patent 14 years

To all whom it may concern:

Be it known that I, Powell Evans, a citizen of the United States, residing in Haverford, Montgomery County, Pennsylvania, have invented a new, original, and ornamental Design for a Combination Fire Grenade and Support, of which the following is a specification, reference being had to the accompanying drawings, forming a part thereof, in which

Fig. 1 is a side elevation of a combination fire grenade and support showing my new design;

Fig. 2 is a front elevation thereof; and
Fig. 3 is a perspective view thereof.

The dominant features of my design reside in the portions shown in full lines.

I claim:

The ornamental design for a combination fire grenade and support, substantially as shown and described.

POWELL EVANS.
